UNITED STATES PATENT OFFICE

SAMUEL SEGAL, OF NEW YORK, N. Y., ASSIGNOR, BY MESNE ASSIGNMENTS, TO SEGAL LOCK & HARDWARE CO., INC., OF NEW YORK, N. Y., A CORPORATION OF NEW YORK

LOCK

Application filed April 18, 1922. Serial No. 554,534.

My invention relates to locks having a locking bolt adapted to enter a suitable keeper to effect a locking of the door or other closure to which the lock is applied, the invention 5 being applicable to rim locks, mortise locks, or locks of various other styles.

The principle object of the invention is the production of a lock of simplicity of construction which shall have spherical members such 10 as balls associated with the locking bolt which shall provide additional locking means serving, in conjunction with said locking bolt, to prevent an unauthorized manipulation or opening of the lock.

15 A further object of the invention is the production of a lock of the above type which shall have included in the mechanism thereof a supplemental bolt adapted to actuate the aforesaid spherical elements.

20 A still further object of the invention is the production of a lock of the pin tumbler type which shall be provided with novel and simple means permitting the adjustment of the position of the cylinder whereby the lock 25 may be easily installed on any door irrespective of its thickness but the adjustment may not be effected unless the key plug has been rotated by the proper key to a predetermined position.

30 To the above and other ends my invention consists in the novel parts and combinations thereof hereinafter more particularly described and then specified in the claims.

In the accompanying drawing showing a 35 practical embodiment of the invention:

Fig. 1 is a section taken through my improved lock as applied to a door.

Fig. 2 is a horizontal section on the line 2—2 of Fig. 1.

Fig. 3 is a horizontal section on the line 3—3 of Fig. 1.

Fig. 4 is a vertical cross-section on the line 4—4 of Fig. 2.

Fig. 5 is a front elevation of the supplemental bolt.

Fig. 6 is an end view of the supplemental bolt shown in Fig. 5.

Fig. 7 is a section taken through a modified 50 form of lock.

Fig. 8 is a front elevation of the lock with the cover plate of the casing removed.

Fig. 9 is a vertical section on the line 9—9 of Fig. 8.

Fig. 10 is a vertical section taken through 55 the locking bolt and supplemental bolt.

Referring in detail to the several figures of the drawing:

1 indicates a door or other closure and 2 the door frame on which which is mounted 60 by suitable screws (not shown) a keeper housing 3 provided with the usual opening 4 adapted to receive a locking bolt to be presently described. A lock casing which is indicated at 5 and which is provided with a removable cover plate 6 is fastened to the door 1 adjacent its edge and the keeper housing 3 by screws (not shown) which pass through the casing, cover plate and into the door. Mounted on the lock casing is an operating 70 handle or knob 7 the shank of which is supported within a bearing 8 having a squared exterior surface which bearing is fastened to the inner side of the front wall of the casing.

9 indicates the body portion of a locking 75 bolt which is adapted to be projected through the slot 4 in the keeper housing and which is supported at its forward end by a slot 10 in the end wall of the lock casing. Said body portion 9 of said locking bolt is provided adjacent one side thereof with a reduced plate 10 preferably integral therewith and the inner end of which is slotted to form arms 11 slidably engaging the squared bearing 8 which acts as a support therefor. The said arms are 80 provided with ribs 12 and their ends with outwardly extending lugs 13. The body 9 of the locking bolt is also provided with horizontal bores 14 as well as transverse bores 15 communicating therewith. Each of said 90 transverse bores holds two spherical members or balls 16 which are retained therein and are prevented from falling outwardly therefrom by beadings 17 formed on the metal of the bolt adjacent the bores but which permit the balls to protrude outwardly from the bores for a certain distance, not quite half-way, as shown in Figs. 1 and 4. The body 9 of the locking bolt is also provided with shoulders 18 adapted to engage the end wall 100

of the lock casing to prevent the bolt from being completely projected out of the casing.

19 indicates the body portion of a supplemental bolt which is provided with forwardly projecting plug members 20 preferably integral therewith having bevelled ends 21 as indicated. These plug members extend with the bores 14 in the body of the locking bolt with which bores they slidably interfit and the body 19 of the supplemental bolt is provided with a shoulder 22 adapted to engage the body of the locking bolt as shown in Fig. 1. 23 indicates arms extending rearwardly from the body 19 and preferably integral therewith. These arms are slidably supported by the squared bearing 8 and they slidably engage the ribs 12 of the arms 11. A compression spring 24 carried within a suitable receptacle or bore in the body 9 of the locking bolt engages a side of the body 19 of the supplemental bolt and tends by its action to slide said supplemental bolt inwardly within the lock casing whereby the ends of the arms 23 will engage the lugs 13.

25 Secured to the inner end of the shank of the knob or handle 7 and rotatable therewith is an arm 25 to the end of which is pivoted one end of a curved link 26, as by a pivot 26', said arm being also provided with a walled recess 27 open at its lower side as shown in Fig. 2. The other end of said curved link is pivoted to a pin 28 carried by the body 19 of the supplemental bolt. Said body 19 is also provided with upper and lower pins 29 and 30 respectively and the curved link 26 is provided with a pin 31. A spring 32 encircles the pin 28 with its ends bearing against the pins 29 and 31, said spring acting to retain the link 26 in the position shown in Fig. 2 or in the position shown in dotted lines in that figure with the pivots or pins 26' and 28 in horizontal alignment. The curved link 26 is also provided with an extension 33 adapted to engage the pin 30 to limit the pivotal movement of said link on the pins or pivots 26' and 28. In some cases it is desirable to have the lower portions of the transverse bores 15 inclined inwardly towards the center thereof as shown at 34 in dotted lines in Fig. 4 so that the spherical members or balls 16 in each bore will tend to move or fall towards each other by gravity unless they are forced or spread outwardly away from each other by the plug members 20 as will be hereinafter explained.

55 The cover plate 6 of the lock casing is provided with two outwardly extending rods 35 riveted thereto and having a series of notches 36 therein. These rods protrude within an annular opening 37 cut through the door 1 and receiving the cylinder 38 of a conventional pin tumbler lock which is provided with the ordinary face plate 39 carrying an escutcheon ring 40. Mounted in cylinder 38 is a key plug 41 to which is connected a spindle 42 supported in a rotatable bearing 43

mounted in the cover plate 6 of the lock casing. The inner end of said spindle carries an operating finger 44 on which is mounted a roller stud 45 engaging within the walled recess 27 on the arm 25.

70 A portion of the key plug 41 is flattened at opposite sides thereof as at 46 which sides are adapted to register with suitable slots 47 cut through opposite sides of the cylinder 38. The cylinder 38 is also provided with two pairs of oppositely disposed perforated heads 48, the heads of each pair being spaced apart from each other and each pair slidably receiving one of the rods 35, whereby the cylinder is supported on said rods. face of a door of smaller thickness than the door shown in full lines in that figure and I have also shown in dotted lines the face plate 39 and heads 48 in the position which they would assume when the device is applied to such door.

When the locking mechanism within the casing 5 is in locked position the parts thereof take the position shown in Fig. 1 with the locking bolt extending within the keeper housing and with the plug portions 20 of the supplemental bolt in extreme forward position within the bores 14, whereby the balls 16 are forcibly spread apart by the bevelled ends 21 of said plugs. It will be thus apparent that even if it were possible to "jimmy" the device and reach the locking bolt and force it rearwardly within the lock casing, however, the plug members 20 of the supplemental bolt are projected within the bores 14 of the locking bolt and the bevelled ends of said plugs are forced intermediate the balls 16 and act to spread them outwardly into the position shown in Fig. 4.

It is manifest that the locking and unlocking movements just described may be just as effectively procured by means of the proper key inserted in the key plug 41 and a rotation of said key plug inasmuch as said plug is connected, as heretofore described, with the arm 25 through the spindle 42, finger 24, roller stud 45 and walled recess 27.

The locking bolt may be withdrawn from the keeper housing by operation or rotation of the handle or knob 7 in the proper direction. Upon the beginning of the rotation thereof the curved link 26 is swung on its pivots 26' and 28 against the action of the spring 32 and the pressure of the spring 26 against the supplemental bolt acts to force said bolt inwardly until the inner ends thereof contact with lugs 13. This partially retracts the plugs 20 within the bores 14 and releases the bevelled ends 21 from engagement with the balls 16. Further rotation of the knob or handle 7 retracts the main locking bolt carrying the supplemental bolt therewith within the casing in an obvious manner whereby the locking bolt is entirely withdrawn from the keeper housing and the door may be swung open. As the main bolt is withdrawn from the keeper the balls 16 strike against the wall of the keeper adjacent the slot 4 which acts to force the balls inwardly within the transverse bores 15 and towards each other, thus permitting the locking bolt to be withdrawn without interference from the balls. If the lower portion of the bores 15 is inclined inwardly as shown at 34 in Fig. 4 the balls 16, as soon as the bevelled ends 21 of the plugs 20 are disengaged therefrom, will roll centrally towards each other by gravity and into engagement with each other which will prevent the balls from striking the end wall of the keeper housing, thus obviating the possibility of any jamming action.

When the bolts are retracted within the casing the inner ends of the bolts, the curved link 26 and other adjacent parts take the position shown in dotted lines in Fig. 2.

To lock the door and project the locking bolt within the keeper housing the handle or knob 7 is rotated in an opposite direction.

This swings the curved link on its pivots to project the locking bolt forwardly. The supplemental bolt travels simultaneously with the locking bolt, the spring 24 acting to momentarily retain the ends of arms 23 in engagement with the lugs 13 and until the end of the locking bolt enters the keeper housing. When the shoulders 18 of the locking bolt engage the end wall of the lock casing, however, the plug members 20 of the supplemental bolt are projected within the bores 14 of the locking bolt and the bevelled ends of said plugs are forced intermediate the balls 16 and act to spread them outwardly into the position shown in Fig. 4.

It is manifest that the locking and unlocking movements just described may be just as effectively procured by means of the proper key inserted in the key plug 41 and a rotation of said key plug inasmuch as said plug is connected, as heretofore described, with the arm 25 through the spindle 42, finger 24, roller stud 45 and walled recess 27.

In the modification illustrated in Figs. 7 to 10 inclusive the forward end or body of the main locking bolt which is indicated at 52 is substantially I-shaped while the rear end of the bolt is slotted as at 53 to form arms 54 slidably engaging the squared bearing 8 for the handle or knob 7. The web portion of the body of the bolt is also provided with a transverse annular opening 55 therein, said body being also provided with stops 56 adapted to engage the end wall of the lock casing and with indentations 57. 58 indicates the supplemental bolts which slidably interfit in the sides of the body of the locking bolt and in said indentations 57 to prevent said supplemental bolts from falling outwardly. Said supplemental bolts carry balls 16 in suitable transverse bores 59 extending therethrough the balls being retained in said bores by suitable beadings as in the preferred form of the invention. As clearly shown in Fig. 10 the lower portions of the bores 59 are inclined inwardly whereby said balls 16 have a tendency to fall towards each other and into engagement with the main locking bolt by the action of gravity.

The supplemental bolts 58 are provided with suitable recesses or receptacles each carrying a compression spring 60 bearing against lugs 61 on the main locking bolt, one of said lugs 61 acting as a stop adapted to engage the extension 33 of the curved link 26 as in the preferred form of the invention. The outer end of said curved link is pivoted by a pin 62 to the main locking bolt and a spring 63 encircles said pin and the ends thereof engage pins 64 and 65 carried by the bolt 52 and link 26 respectively. The function of said spring 63 is the same as in the preferred form of the invention. The bolt 52 also carries a pin 66 the ends of which slidably engage in slots 67 in the supplemental bolts 58.

The operation of the modified device is very similar to that of the preferred form of the invention. When the bolt 52 has been projected into the keeper housing the various parts take the position shown in the several figures. To retract the bolt 52 within the lock casing the knob or handle 7 is rotated in the proper direction, the bolt 52 begins to move inwardly, the spring 60 acting to hold 10 the supplemental bolts 58 against movement momentarily. When the opening 55 in the bolt 52 registers with the transverse bores 59 in the supplemental bolts the balls 16 fall inwardly by the action of gravity and extend 15 partially within the opening 55. Meanwhile the ends of the pin 66 have reached the ends of the slots 67 in the supplemental bolts so that a continued rotation of the handle or knob retracts the bolt 52 carrying the bolts 20 58 with it within the casing, the balls 16 clearing the end wall of the keeper housing in an obvious manner. To project the bolt within the keeper, the reverse movements of the parts obtain, the continued 25 movement of the bolt 52 after the shoulders 56 have engaged the end walls of the lock casing acting to force the balls 16 outwardly and out of the opening 15.

What I claim as my invention is:—

30 1. In a lock, a casing containing the locking mechanism, a cylinder, a key plug therein, means connecting the key plug and locking mechanism, means extending from said casing on which said cylinder is slidably 35 mounted and means for locking said cylinder on said extending means, said locking means being adapted to be released only when said key plug has been rotated to a predetermined position by means of the 40 proper key therefor.

2. In a lock, a casing containing the locking mechanism, a cylinder, a key plug therein, means connecting the key plug and locking mechanism, means associated with said 45 casing on which said cylinder is slidably and adjustably mounted and means engaging said key plug and said associated means for locking said cylinder on said associated means and adapted to be released to permit 50 movement of said cylinder only when said key plug has been rotated to a predetermined position by means of the proper key therefor.

55 3. In a lock, a casing containing the locking mechanism, a cylinder, a key plug therein, means connecting the key plug and locking mechanism, means associated with said casing on which said cylinder is slidably and adjustably mounted and spring means en- 60 gaging said key plug and said associated means for locking said cylinder on said associated means in adjusted position and adapted to be released from engagement with said key plug and associated means to permit movement of said cylinder on said as-

sociated means only when said key plug has been rotated to a predetermined position by means of the proper key therefor.

4. In a lock, a casing containing the locking mechanism, a cylinder, a key plug therein, means connecting the key plug and locking mechanism, means associated with said casing on which said cylinder is slidably and adjustably mounted and provided with notches therein and spring means engaging 70 the notches in said associated means for holding said cylinder thereon in any desired adjusted position.

5. In a lock, a casing containing the locking mechanism, a cylinder, a key plug therein, means connecting the key plug and locking mechanism, means associated with said casing on which said cylinder is slidably and adjustably mounted and provided with notches therein and spring means engaging 80 said key plug and said notches for locking said cylinder on said associated means in adjusted position and adapted to be released from engagement with said key plug and to permit movement of said cylinder on said 85 associated means only when said key plug has been rotated to a predetermined position by means of the proper key therefor.

6. In a lock, a casing containing the locking mechanism, a cylinder, a key plug therein, 90 having a flat side, means connecting the key plug and locking mechanism, means associated with said casing on which said cylinder is slidably and adjustably mounted and means adapted to engage the flat side of said 95 key plug and said associated means for locking said cylinder thereon.

7. In a lock, a casing containing the locking mechanism, a cylinder provided with a slot therein, a key plug within said cylinder 100 having a flat side adapted to register with said slot, means connecting the key plug and locking mechanism, means associated with said casing on which said cylinder is slidably mounted and means adapted to extend within 105 said slot and to engage the flat side of said key plug and said associated means for locking said cylinder thereon.

8. In a lock, a casing containing the locking mechanism, a cylinder provided with a slot therein, a key plug within said cylinder, means connecting the key plug and locking mechanism, means associated with said casing on which said cylinder is slidably and adjustably mounted and spring means 110 adapted to extend within said slot and to engage said key plug and said associated means for holding said cylinder in adjusted position thereon.

9. In a lock, a casing containing the locking mechanism, a cylinder, a head on said cylinder, a key plug in said cylinder, means connecting the key plug and locking mechanism, a rod on said casing slidably receiving 115 said head and means engaging said rod 120

- and said key plug for locking said cylinder in position.
10. In a lock, a casing containing the locking mechanism, a cylinder having a slot therein, a head on said cylinder, a key plug in said cylinder, means connecting the key plug and locking mechanism, a rod on said casing slidably receiving said head and a spring entering the slot in said cylinder and 10 engaging said rod for locking the cylinder in position.
11. In a lock, a casing containing the locking mechanism, a cylinder having a slot therein, a pair of heads on said cylinder with 15 a space therebetween, a key plug in said cylinder having a flat side and adapted to register with said slot, means connecting the key plug and locking mechanism, a notched rod fastened on said casing and slidably receiving 20 said heads and a spring in the space intermediate said heads and entering said slot and engaging said key plug and a notch in said rod for holding the cylinder in position.
12. In a lock, a locking bolt, a keeper, 25 means for actuating said locking bolt to project it into said keeper and a spherical locking member carried by and movable with said locking bolt, said member being engageable with said keeper to prevent a retraction 30 of said bolt.
13. In a lock, a locking bolt, a keeper, means for actuating said locking bolt to project it into said keeper and retract the same therefrom and a ball associated with said 35 locking bolt and adapted to be thrust outwardly when said locking bolt is projected into said keeper by said actuating means.
14. In a lock, a locking bolt, a keeper, means for actuating said locking bolt and 40 a locking device adapted to be thrust outwardly from the side face of said bolt and into locking position when said locking bolt is projected into said keeper by said actuating means and to fall into normal position 45 by gravity when said locking bolt is retracted from said keeper.
15. In a lock, a locking bolt, a keeper for receiving said locking bolt, a supplemental locking bolt, locking means associated with 50 said locking bolt and adapted to be thrust into locked position by said supplemental bolt when said locking bolt is projected into said keeper and means tending to move said locking bolt and supplemental bolt in opposite directions.
16. In a lock, a locking bolt, a keeper for receiving said locking bolt, a supplemental locking bolt slidable on said locking bolt and a spherical locking member associated with 55 said locking bolt and adapted to be thrust outwardly by said supplemental bolt when said locking bolt is projected into said keeper.
17. In a lock, a locking bolt, a keeper for receiving said locking bolt, a supplemental bolt slidable on said locking bolt, a locking 60
- member associated with said locking bolt and adapted to be thrust into locking position by said supplemental bolt when said locking bolt is projected into said keeper and spring means engaging each of said bolts and acting to move them in opposite directions.
18. In a lock, a locking bolt, a keeper for receiving said locking bolt, a supplemental bolt, a locking member associated with said locking bolt and adapted to be thrust into locking position by said supplemental bolt when said locking bolt is projected into said keeper, spring means engaging each of said bolts and acting to move them in opposite directions and means for limiting the movement of said bolts in opposite directions.
19. In a lock, a locking bolt, a keeper for receiving said locking bolt, a supplemental bolt, a spherical locking member associated with said locking bolt and adapted to be forced into locking position by said supplemental bolt when said locking bolt is projected into said keeper and a spring carried by one of said bolts and bearing against the other thereof and acting to move said bolts in opposite directions.
20. In a lock, a locking bolt, a keeper for receiving said locking bolt, a supplemental bolt and a locking ball associated with said locking bolt and adapted to be forced into operative position when engaged by said supplemental bolt and to assume an inoperative position when disengaged by said supplemental bolt.
21. In a lock, a locking bolt, a keeper for receiving said locking bolt, a supplemental bolt and a locking ball associated with said locking bolt and adapted to be thrust outwardly into operative position by said supplemental bolt and to fall inwardly by gravity into inoperative position when disengaged therefrom.
22. In a lock, a locking bolt, a keeper for receiving said locking bolt, a supplemental bolt and a pair of spherical locking members carried by said locking bolt and adapted to be thrust outwardly away from each other into locking position when said locking bolt is actuated.
23. In a lock, a locking bolt, a spherical locking member associated with said bolt, a keeper for receiving said locking bolt and a supplemental bolt adapted to actuate said locking bolt and said spherical member when said locking bolt has entered said keeper.
24. In a lock, a locking bolt, a keeper for receiving said locking bolt, a supplemental bolt adapted to actuate said locking bolt and engaging the same by a sliding contact whereby movement of one bolt may be effected without movement of the other and a locking member adapted to be actuated by said supplemental bolt when said locking bolt has entered said keeper.

25. In a lock, a locking bolt, a supplemental bolt adapted to actuate said locking bolt and engaging the same by a sliding contact whereby movement of one bolt may be effected for 5 a given distance without movement of the other and a locking member adapted to be actuated by one of said bolts after the other has reached a predetermined position in its travel.
- 10 26. In a lock, a locking bolt, a supplemental bolt adapted to actuate said locking bolt and engaging the same by a sliding contact whereby movement of one bolt may be effected for 15 a given distance without movement of the other, a spherical locking member adapted to be forced into locking position by one of said bolts after the other has reached a predetermined position in its travel and means for actuating said supplemental bolt.
- 20 27. In a lock, a locking bolt, a supplemental bolt adapted to actuate said locking bolt and engaging the same by a sliding contact whereby movement of one may be effected for a given distance without movement of the 25 other, a pair of locking balls adapted to be spread apart and forced into locking position by one of said bolts after the other has reached a predetermined position in its travel, means tending to force said bolts in opposite directions and means for actuating said supplemental bolt.
- 30 28. In a lock, a locking bolt and a supplemental bolt, one of said bolts being provided with a horizontal and a transverse bore there- 35 in communicating with each other, a locking member mounted in said transverse bore and means on the other of said bolts slidably ex- tending within said horizontal bore and adapted to strike said locking member and 40 thrust the same outwardly into locking position.
- 45 29. In a lock, a locking bolt provided with horizontal and transverse bores therein com- munitcating with each spherical locking mem- 50 ber mounted in said transverse bores and a supplemental bolt adapted to actuate said locking bolt and provided with plug members entering said horizontal bores and adapted to spread said spherical locking members apart into locking position when said locking bolt enters said keeper.
- 55 30. A lock, including, in combination, a bolt, a bolt-projecting member slidably within said bolt, actuating means connected with said member, and means whereby upon said actuating means being operated to project said member and bolt connected therewith, the latter and said member will initially move as one unit and subsequently be shifted relatively to each other.
- 60 31. A lock, including, in combination, a bolt, a bolt-projecting member slidably within said bolt, actuating means connected with said member, and means whereby upon said actuating means being operated to project
- 70 said member and bolt connected therewith, the latter and said member will initially move as one unit, said bolt subsequently ceasing to move, and said member continuing its movements.
- 75 32. A lock, including, in combination, a bolt, a bolt-shifting member movably associated with said bolt, actuating means connected with said member, means whereby upon said actuating means being operated said member and bolt will initially move as one unit, said bolt subsequently ceasing to move, and said member continuing its movements, and locking means carried within said bolt and shiftable to a position beyond the 80 same during the final stage of movement of said member.
- 85 33. A lock, including, in combination, a bolt, a bolt-shifting member movably carried by the same, actuating means connected with said member to move the latter and said bolt as one unit, means for interrupting the movement of said bolt while permitting a continued movement of said member, locking means carried within said bolt and shiftable to a 90 position beyond the same during said continued movement, and means whereby a return movement of said actuating means will cause said locking means to be rendered inoperative to subsequently retract said bolt.
- 95 34. A lock, including, in combination, a bolt projectible into a keeper, supplemental locking means housed within said bolt and projectible beyond the same, and means connected with said supplemental means for actuating the same and projecting said bolt, whereby upon said bolt being forcibly re- tracted, said actuating means will remain inoperative, said supplemental locking means preventing a retraction of said bolt from 100 within said keeper.
- 105 35. A lock, including, in combination, a bolt, supplemental locking means carried by said bolt, means for rendering said supplemental means operative upon said bolt being projected, means permitting the force of gravity to act upon said supplemental locking means to render the same inoperative upon said bolt being retracted, and means for positively rendering said locking means inopera- 110 tive.
- 115 36. A lock, including, in combination, a bolt, means extendible from the side faces of the same and acting to supplement the locking action of said bolt, means for render- 120 ing said supplemental locking means opera- tive, means permitting the same to become in- operative, and further means for positively forcing said locking members into inopera- 125 tive position.
- 130 37. A lock, including in combination, a main bolt, a supplemental bolt associated therewith, means for projecting both of said bolts, and means for urging a retraction of one only of said bolts.

38. A device of the character described, including in combination, a bolt, a bolt-projecting member slidably carried within the body of said bolt, and actuating means constantly and movably connected with said member.

39. A lock, including a bolt, a keeper therefor, means for actuating said bolt, a plurality of locking means acting under the influence of gravity to be normally housed within said bolt, and means for moving said locking means in opposite directions with respect to each other and beyond the side faces to engage with said keeper and prevent a retraction of the bolt therefrom.

40. A lock, including, in combination, a main locking bolt for entry into a keeper, means associated with said bolt and engageable with said keeper for preventing a retraction of said bolt, a supplemental bolt controlling the operation of said means, and main bolt-actuating means constantly connected with said supplemental bolt.

41. A lock, including a bolt, a keeper therefor, means for actuating said bolt, a plurality of spherical locking relatively movable means normally housed within said bolt adjacent the side faces thereof and mounted for slideable movement in opposite directions, and means for actuating said last-named means to engage with said keeper to prevent a retraction of the bolt therefrom.

42. A lock, including, in combination, a cylinder and plug rotatable therein, a lock mechanism connected with said plug and to be operated by the rotation thereof, means for supporting said cylinder for reciprocation with respect to said mechanism, and means actuated by said plug for locking said cylinder against adjustment.

43. A lock, including, in combination, a cylinder and plug rotatable therein, a lock mechanism connected with said plug and to be operated by the rotation thereof, a rod connected with said mechanism and slidably engaging said cylinder to support the latter, and means actuated by said plug and locking said cylinder against movement with respect to said mechanism.

44. A lock, including, in combination, a cylinder and plug rotatable therein, a lock mechanism connected with said plug and to be operated by the rotation thereof, a notched rod connected with said mechanism and slidably engaging said cylinder to support the latter, and means carried by said cylinder and engaging a notch thereof to prevent movement of said cylinder with respect to said mechanism, said plug engaging said last-named means to prevent a retraction thereof from within said notch.

Signed at New York in the county of New York and State of New York, this 14th day of April, A. D. 1922.
